UNITED STATES PATENT OFFICE.

FRANK L. YOUNG, OF BOSTON, MASSACHUSETTS.

APPARATUS FOR TIN-PLATING.

SPECIFICATION forming part of Letters Patent No. 786,336, dated April 4, 1905.

Application filed February 1, 1904. Serial No. 191,438.

To all whom it may concern:

Be it known that I, FRANK L. YOUNG, a citizen of the United States, residing at Boston, county of Suffolk, State of Massachusetts, have invented an Improvement in Apparatus for Tin-Plating, of which the following description, in connection with the accompanying drawings, is a specification, like letters on the drawings representing like parts.

10 My invention relates to an apparatus for plating tin, and has especially to do with the finishing of the tin-plate, and is designed more particularly to remedy defects found to exist in apparatus now in use.

15 The nature of the invention will appear from the following specification and is defined in the appended claims.

Figure 1 is a side view, chiefly in section, of the entire apparatus. Fig. 2 is an end view 20 of the same.

A represents a pot containing molten tin, (indicated at B.) In the upper part of the pot a layer of oil (indicated at C) is provided. Above the pot and mounted thereon is a pair 25 of squeeze delivery-rolls D D, driven by a pulley E and intermeshing gears d d. The apparatus thus far described has been commonly used. The plate of sheet-iron to be tinned is passed through the bath of molten tin B in any usual manner, not here necessary to describe. It is then passed upward 30 through the bath of oil into the nip of the rolls D D, which rolls themselves are so placed as to dip into the oil. The result of this operation is 35 that the plate F of sheet-iron covered with tin and forming the tin-plate is subjected to pressure between the rolls D D, which finish off the plate and compress it and its coating of tin to the desired gage or thickness. The 40 object of passing the tin through the oil and coating the rolls D D with oil is mainly to prevent the coating of tin from being removed from the plate during its passage through the rolls. In using this apparatus it has been 45 found that the plates of tin after coming from the apparatus are frequently and usually stained, and polishing and dusting operations, requiring much time and expense, are necessary to remove these oil stains. I have come 50 to the conclusion that this is due to the fact

that oil collects in the jaws of the rolls D D after the passage of one plate and before the entrance of the succeeding plate into the nip of the rolls. It will be noted that the passage of the plates F being necessarily more 55 or less intermittent the rolls D are carrying oil upward, and this oil naturally remains and is deposited in the jaws of the rolls at the point marked G. When the next plate enters, it meets this mass of oil, with which it becomes coated 60 at one end, and thereby the objectionable stains are formed upon the plate. In my apparatus, designed to obviate this defect, I mount above and adjacent to the rolls D D a pair of auxiliary squeeze-rolls H H, which are 65 preferably driven at the same speed as the rolls D D and may be so driven by intermeshing gears h h, carried by the two rolls H H and intermeshing gears K K, carried by one of each of the pairs of rolls H H, D D. Each 70 of the rolls H H, I provide with means for removing oil from the surface of the rolls. This means illustrated herein consists of a pair of pivotally-mounted scrapers M M, held in contact with the roll H by springs m. Between these scrapers is placed an absorbent material, (shown at O,) capable of withstanding heat. It will thus be seen that when the plate F passes from the rolls D D, covered 75 more or less with oil, it enters the nip of the rolls H H and the oil upon the surface of the plate F passes to the surface of the rolls H H, from which surface it is removed by suitable means, as herein illustrated, so that the surface of the rolls H H as they come in contact with the plate are substantially clean. The result of the passage of the plate through 80 the auxiliary rolls H H thus operates to remove the oil therefrom which causes the objectionable stains, and at the same time it 85 further finishes and compresses the plate F as desired, the result being a smooth unstained tin-plate.

The scraping means may be varied as desired. They may remove the oil entirely from 90 the face of the rolls H, or if it be found that a slight amount of oil should be left upon the rolls they may readily be adjusted to allow therefor; but it will usually be found that sufficient oil is brought along with the plate F, 95 100

which it is the object of this device to remove to prevent any damage to the plate during its passage through the rolls H H.

I have illustrated two metallic scrapers M M; 5 but only one may in some instances be found sufficient. To render the rolls quite clean, I have illustrated an absorbent material O, which may be of mineral wool, asbestos, or any such absorbent which will stand the heat; 10 but this may or may not be used, as found desirable. The second scraper acts to remove any lint or material which might pass onto the roll from the absorbent material.

This apparatus results not only in the prevention of the stains upon the plate, but also 15 a large saving of oil, since the oil removed by the rolls H H can be passed back into the pot A, and the oil taken up by the absorbent material O may be removed therefrom by boiling 20 or otherwise.

While I have shown a particular form of apparatus, it will be understood that my invention is not limited thereto, since various means of applying oil to the rolls D may be used, 25 and the arrangement of the rolls is not limited to a vertical sequence, as herein shown. Furthermore, while I have described the apparatus as for tin-plating, for which it is especially designed, I do not desire to restrict myself 30 to the use of the device for this purpose alone, and when I use the term "tin-plating" in the specification and claims I refer to plating with any metal which demands treatment in a similar way to tin.

35 Having described my invention, what I claim as new, and desire to secure by Letters Patent, is—

1. In a tin-plating apparatus; a pot to contain molten tin; a pair of squeeze delivery- 40 rolls adjacent thereto; means for supplying oil to the surface of said delivery-rolls; a pair of auxiliary squeeze-rolls beyond said delivery-rolls and out of contact with the oil-supply; and means for removing oil from the surface 45 of said auxiliary rolls.

2. In a tin-plating apparatus; a pot to contain molten tin; a pair of squeeze delivery-rolls located above and adjacent thereto; means for supplying oil to the surface of said delivery- 50 rolls; a pair of auxiliary rolls above said delivery-rolls and out of contact with the oil-supply; and means for removing oil from the surface of each of said auxiliary rolls.

ery-rolls; a pair of auxiliary rolls above said 50 delivery-rolls and out of contact with the oil-supply; and means for removing oil from the surface of said auxiliary rolls.

3. In a tin-plating apparatus; a pot to contain molten tin; a pair of squeeze delivery- 55 rolls adjacent thereto; means for supplying oil to the surface of said delivery-rolls; a pair of auxiliary squeeze-rolls beyond said delivery-rolls and out of contact with the oil-supply; and a scraper adjacent to and acting upon the surface of each of said auxiliary rolls to remove oil from the surface thereof.

4. In a tin-plating apparatus; a pot to contain molten tin; a pair of squeeze delivery- 60 rolls located above and adjacent thereto; means 65 for supplying oil to the surface of said delivery-rolls; a pair of auxiliary rolls above said delivery-rolls and out of contact with the oil-supply; and a scraper adjacent to and acting upon the surface of each of said auxiliary rolls 70 to remove oil from the surface thereof.

5. In a tin-plating apparatus; a pot to contain molten tin; a pair of squeeze delivery- 75 rolls adjacent thereto; means for supplying oil to the surface of said delivery-rolls; a pair of auxiliary squeeze-rolls beyond said delivery-rolls; a pair of scrapers adjacent to and acting upon the surface of each of said auxiliary rolls; and absorbent material between said pairs of scrapers whereby oil is removed from 80 the surface of said auxiliary rolls.

6. In a tin-plating apparatus; a pot to contain molten tin; a pair of squeeze delivery- 85 rolls located above and adjacent thereto; means for supplying oil to the surface of said delivery-rolls; a pair of auxiliary rolls above said delivery-rolls; a pair of scrapers adjacent to and acting upon the surface of each of said auxiliary rolls; and absorbent material between said pairs of scrapers whereby oil is removed from 90 the surface of said auxiliary rolls.

In testimony whereof I have signed my name to this specification in the presence of two subscribing witnesses.

FRANK L. YOUNG.
